MEANS FOR CONTROLLING THE VALUE OF AN ELECTRIC CURRENT

Application filed October 11, 1928. Serial No. 311,769.

This invention relates to means for controlling the value of the current in an electrical circuit.

One means for this purpose which is in general use in radio operation comprises a ballast resistance which is placed in the circuit in series with the load. A property of a ballast resistance is that it increases in resistance upon an increase of current flowing therethrough, the commercial ballast resistances being adapted to increase approximately 100% in resistance with a 10% change in the current which they are intended to carry.

Owing to the fact that ballast resistances according to present practice are placed in the circuit in series with the load, a wattage of a comparatively large amount is consumed by such resistances. For instance if a variation in the supply voltage of from 100 to 125 is to be taken care of in a circuit in which the limit of current variation is one ampere in a normal supply of ten amperes, the ballast resistance must be such that at a line voltage of 100 the lost volts across the ballast resistance will be 25 volts so that by a change in its resistance of 100% due to a change in current flow of one ampere the increase of 25 volts in the supply circuit can be taken care of and consumed by the ballast resistance. Thus for a constant load voltage of 75 volts the voltage drop across the ballast resistance will have a value equal to one-third of that of the load voltage while the voltage drop across the ballast resistance with a line voltage of 125 volts will have a value equal to two-thirds of that of the load voltage.

The object of the present invention is to effect a control of the current through a circuit by means which will consume only a comparatively small wattage.

According to one feature of this invention the ballast resistance is provided in a circuit in parallel with the load and such ballast resistance is associated with means which is adapted to vary a resistance in the circuit, the variation in such resistance being proportionately higher than the variation in the voltage of the supply circuit.

In order that the invention may be clearly

understood reference is made to the accompanying drawing which illustrates by way of example two embodiments of the invention and in which:

Figure 1 is an illustration of a circuit containing a ballast resistance according to present practice. 55

Figure 2 is an illustration of means for varying a resistance in an electrical circuit;

Figure 3 is an illustration of one form of 60 my invention showing a ballast resistance in combination with the means illustrated in Fig. 2.

Figure 4 is a modified form of my invention. 65

Referring to Figure 1 of the drawings, a supply voltage is provided for the load 1 by a generator 2, a ballast resistance 3 being provided in series with the load 1.

Presuming that the circuit consumes 10 amperes and that the supply voltage varies between 100 and 125 volts then the ballast resistance 3 must be able to consume approximately the additional 25 volts to keep the load voltage substantially constant. 70

As previously stated the property of a commercial ballast resistance is such that it increases approximately 100% in resistance with a 10% change in current; thus in order that the additional 25 volts will be consumed 80 by the ballast resistance by a change of current from 10 amperes to 11 amperes, the initial voltage lost across the ballast resistance must be 25 volts. The approximate results obtained by a circuit such as that illustrated 85 in Fig. 1 ignoring the effect of the small rise in voltage across the load are shown in the following table:

Line voltage	Current	Voltage across ballast	Voltage at load	90
100	10	25	75	
125	11	50	75	95

It will be clearly seen from this table that with a supply voltage of 100 volts the ballast resistance consumes a wattage which is substantially one-third of that consumed by the load and that when the supply voltage is 125 100

volts the ballast resistance consumes a wattage which is substantially two-thirds of that consumed by the load.

This considerable consumption in the wattage of the circuit by the ballast resistance is due to the fact that the ballast resistance is in series with the load and that the full current passes through such ballast resistance.

According to the present invention the ballast resistance is arranged in parallel with the load and is so connected that only a small current relatively to the full load current passes through the ballast resistance. Such ballast resistance is arranged so as to control means which will cause a sufficient variation in a resistance provided in the main circuit as to keep the load voltage substantially constant.

Any suitable means for controlling a resistance in the load circuit may be provided in combination with the ballast resistance, such as for instance the means illustrated in Fig. 2 of the drawings.

Referring to this figure a supply voltage for the load 1 is provided by the generator 2 and a resistance 4, such as a carbon pile, which is maintained under compression by means of a spring armature 5, is provided in the circuit in series with the load. A solenoid 6 is also provided in the circuit, this solenoid being in parallel with the load and being in associated relation with the armature 5 so that the pressure exerted by the armature 5 on the carbon pile 4 will be varied by any change in the value of the current flowing through the solenoid 6. In this construction, however, the variation in pressure on the carbon pile would vary directly with the variations in the line voltage and such construction in itself would not effect such a control of the circuit as would maintain the load voltage substantially constant.

According to one form of the present invention as illustrated in Fig. 3 of the drawings, a ballast resistance 7 is connected in parallel with the solenoid 6. A comparatively high resistance 8 is connected between the junction point 9 of the ballast resistance 7 and solenoid 6 and the supply line 10. Assuming that the ballast resistance 7 has a voltage drop across it of one volt when the line voltage is 100 volts, that the resistance 8 is so chosen that the current flowing therethrough is one ampere and that the resistance of the solenoid 6 is approximately 100 ohms, then the current flowing through said solenoid 6 will be approximately $\frac{1}{100}$ of that flowing through the ballast resistance 7, that is slightly less than one ampere will flow through the ballast resistance 7 and slightly less than .01 amperes will flow through the solenoid 6. The ballast resistance will have practically no controlling effect upon the current flowing through the resistance 8 owing to the

small voltage drop across such ballast resistance. With an increase of 10% in the current flowing through the ballast resistance, however, due to an increase in the line voltage to 110 volts, the voltage drop across such resistance will increase 100% owing to the property of ballast resistances as previously stated; thus the drop in voltage across the ballast resistance will be increased to practically two volts. This voltage drop of 2 volts will also be the voltage drop across the solenoid 6 since it is in parallel with the ballast resistance 7 and since the resistance of this solenoid is constant the current therethrough will also increase 100% and will be approximately .02 amperes.

The current flowing through the solenoid 6 will therefore vary substantially 100% for a change in the line voltage of 10%. Consequently the pull on the armature 5 will increase 100% and a substantially great change in the resistance of the carbon pile 4 can be effected by a comparatively small change in the line voltage. Thus by a suitable construction of the carbon pile 4 the load voltage applied to the load 1 can be maintained substantially constant.

With this construction only a small current passes through the ballast resistance as compared with that which passes through the load 1, and thus the wattage consumed by the ballast resistance 7 will be comparatively small as compared with that consumed by the load.

The resistance controlled by the solenoid 6 may be of any suitable kind and this resistance may be such that when the supply voltage is at its minimum, the resistance in series with the load will be practically negligible.

Other means than a solenoid and armature for controlling the resistance in series with the load may be provided and as an example of a further method of controlling such resistance reference is made to Fig. 4 of the drawing. In this figure the ballast resistance 7 and the resistance 8 are provided in series in a circuit parallel with the load circuit and the ballast resistance 7 is located within an air chamber 11 which is associated with the carbon pile 4 in such manner that an expansion of the air in such chamber caused by a variation in the heating effect of the ballast resistance 7 due to its variation in resistance, will effect a variation in the pressure applied to the carbon pile. The variation in the pressure applied to the carbon pile by the variation of the pressure of the air in the chamber 11 will be correspondingly much greater than the variation in the resistance of the ballast resistance 7 and thus the volume of air enclosed within the chamber 11 may be so chosen that the correct variation in the resistance of the carbon pile 4 necessary for maintaining a substantially constant load voltage will be effected.

The modifications described and illustrated in the specification are given by way of example only and it will be obvious to those skilled in the art that other means associated with a ballast resistance arranged in the circuit parallel with the load can be devised for effecting the desired control of the load voltage.

What I claim is:—

- 10 1. Means for maintaining the current in an electrical circuit substantially constant comprising a ballast resistance in parallel with the load of said circuit, a variable resistance in said circuit, and means associated with said ballast resistance which is adapted to be influenced by the change in the value of such ballast resistance due to a change in the current flowing therethrough, for controlling the value of said variable resistance.
- 20 2. Means for maintaining the current in an electrical circuit substantially constant comprising a variable resistance within said circuit, a ballast resistance in parallel with the load of said circuit, a solenoid in parallel with said ballast resistance and means adapted to be influenced by the change in the current flowing through said solenoid for effecting a variation of the amount of said resistance.
- 30 3. Means for maintaining the current in an electrical circuit substantially constant comprising a resistance in said circuit, a ballast resistance in parallel with the load of said circuit, a solenoid in parallel with said ballast resistance, a resistance interposed between said ballast resistance and solenoid, and said circuit, and means influenced by the change in the value of the current flowing through said solenoid for effecting the variation in the value of the resistance in said circuit.
- 40 4. Means for maintaining the current in an electrical circuit substantially constant comprising a solenoid in parallel with the load of said circuit, a ballast resistance in parallel with said solenoid, a resistance interposed between said solenoid and ballast resistance, and said circuit, an armature adapted to be influenced by the change in the value of the current flowing through said solenoid, a resistance in said circuit, and means whereby movement of said armature will effect a variation in the value of said resistance in said circuit.
- 50 5. Means for maintaining the current in an electrical circuit substantially constant comprising a ballast resistance in parallel with the load of said circuit, a resistance in said circuit comprising a carbon pile and means influenced by the change in the ballast resistance due to a change in the current flowing therethrough for controlling the pressure exerted on said carbon pile to vary the resistance thereof.

In testimony whereof I affix my signature.

65 SAMUEL RUTTENBERG.
